CLAIM

The ornamental design for wrist pen holder, substantially as shown and described.

DESCRIPTION

FIG. 1 is a top plan view of a wrist pen holder showing my new design in extended position, the bottom surface being substantially plain and unornamented;

FIG. 2 is a perspective view thereof;

FIG. 3 is a top plan view of another embodiment of the wrist pen holder of FIG. 1, the bottom surface being substantially plain and ornamented; and

FIG. 4 is a perspective view thereof.
